OF CLINTON, IOWA, A CORPORATION OF IOWA

WINDOW JAMB, CASING, AND BLIND STOP CONSTRUCTION

Application filed April 24, 1930. Serial No. 446,940.

The object of this invention is to provide a window jamb, casing and blind stop construction that is simple, durable and comparatively easy to manufacture.

5 More particularly, it is my object to provide a construction for window frames in which the side jambs and side casings are connected with a tongue and groove joint, the head jamb and casing are connected with 10 a rabbeted joint, the upper ends of the side casing are connected with the head casing by a tongue and groove joint, and the blind stop is connected to the jamb by a dove-tailed tongue and groove connection. 15 Still a further object is to provide means whereby an effective weather tight joint is provided between the head and side casings and the head and side jambs and yet a tongue and groove connection can be provided between the side casings and head casing so that the outer surface of the casings can be accurately aligned with each other.

Another object is to provide a dove-tailed tongue and groove connection for the blind stop so that it may be locked in position by the casings when they are applied to the jambs more rigidly than is possible when attaching the blind stop by either screws or nails alone. This construction makes removal of the blind stop very difficult for burglars so that the window sashes cannot be removed after the blind stops are removed for gaining access to the building.

A further object is to provide a tongue 35 and groove joint between the side casings and side jambs, whereby a blind stop having a dove-tailed connection with the side jamb is made rigid and permanent due to the locking of the dove-tailed tongue of the blind stop.

Still a further object is to improve the weather tight qualities, appearance and ease of aligning parts of a window frame and otherwise improve the frame as hereinafter set forth.

With these and other objects in view my invention consists in the construction, arrangement and combination of the various parts of my device, whereby the objects contemplated are attained, as hereinafter more

fully set forth, pointed out in my claims, and illustrated in the accompanying drawings, in which:—

Figure 1 is an outside elevation of a window frame embodying my invention. 55

Figure 2 is a vertical, sectional view on an enlarged scale and taken on the line 2—2 of Figure 1.

Figure 3 is a horizontal, sectional view on an enlarged scale taken on the line 3—3 of 60 Figure 1.

Figure 4 is a separated perspective view of portions of the head jamb, side jamb, head casing, and side casing.

Figure 5 is an inside separated perspective 65 view of the upper end of the side casing and one end of the head casing as viewed from below.

Figure 6 is a perspective view of the upper end of the side casing. 70

Figure 7 is a perspective view of the upper end of a side jamb and a blind stop normally coacting therewith being illustrated separated therefrom; and

Figure 8 is a sectional view similar to the 75 upper part of Figure 2 showing a modified form of construction.

On the accompanying drawings I have used the reference character A to indicate generally a window frame. The window 80 frame A includes a sill 10, side jambs 12 and a head jamb 14. It further includes side casings 16 and a head casing 18.

The side jambs 12 are provided at their outer edges with tongues 20. The side casings 16 are provided in their inner faces with grooves 22 to coact with the tongues 20 as best shown in Figure 3 of the drawings. Thus, a weather tight joint is provided between the side jambs and side casings which 90 accurately aligns all of these parts relative to each other.

In providing this tongue and groove joint between the jambs and casings of the window frame A, it would be desirable to run 95 the tongue and groove joint along both side casings and also across the head casing. It is also desirable to have a tongue and groove joint between the top ends of the side casing and the head casing. 100

Unfortunately, a window frame cannot be conveniently assembled when so constructed. Therefore, it is necessary to substitute some other form of weather resisting joint either 5 between the head jamb and head casing or between the side casing and head casing. Since it is more important to retain the tongue and groove joint between the side and head casings, I have chosen a rabbetted joint 10 for use between the head jamb and head casing.

For aligning the head casing 18 with the upper ends of the side casings 16, I provide a groove 24 in the lower edge of the head casing 18 and tongues 26 formed on the upper ends of the side casings 16 to coact with the groove 24. Since I have retained a tongue and groove connection between the side jambs and head jamb, and it is necessary to 20 provide another type of joint between the head jamb and head casing, I project the outer edge of the head jamb 14 outwardly until it is substantially flush with the outer edges of the tongues 20. I then form a rabbet 30 in the inner lower corner of the head casing 18 so as to provide the rabbetted joint 25 between head jamb and head casing as already referred to and as best shown in Figure 2.

30 This arrangement permits assembly of the side and head jambs, the application of the side casings to the side jambs, and lastly—the application of the head casing to the parts of the window frame already assembled 35 which can be slid directly downward into place, thus joining it with the tongues on the upper ends of the side casings and with the outer edge of the head casing. Such a joint is not quite as good as a tongue and groove 40 joint, but a tongue and groove joint is not as necessary at the top of a window frame A as to the sides thereof or between the side casings and head casing.

It might also be noted that this arrangement 45 entirely eliminates any secondary operations of cutting off the tongues of any members near any of the joints as is necessary in so many of the present types of window frame constructions.

50 My construction also permits the use of a groove extending the full length in the lower edge of the head casing with which an upwardly extending tongue or a screen frame or storm sash may coact.

55 It will be noted that the rabbet 30 ends short of the ends of the head casing 18 as indicated at 31 so as not to leave an unsightly opening at the ends of the head casing which might not in all cases be covered 60 with siding, stucco or other wall coverings.

For securing the proper alignment of the side jambs 12 with the head jamb 14, I preferably form a dado 29 in the undersurface 65 of the head jamb 14 as best shown in Figure 4.

The tongue and groove joint between the side jambs and side casings and the rabbetted joint between the head jamb and head casing do not interfere in any way with the dado joint 29.

In present day constructions it is the usual practice to provide a blind stop consisting of a narrow strip inserted between the outer edge of the jamb and the inner surface of the casing member.

This requires that two joints must be weatherproof.

In the construction I disclose, one of these joints has been entirely eliminated and the one that is left is a tongue and groove joint 80 at the sides of the window frame and a rabbeted construction at the head thereof.

When the jambs extend to the casings as just described it is necessary to apply a blind stop to the inner face of the jamb. This is usually done with nails or screws. I provide a more secure means for their application as will now be described.

In connection with the window frame A I provide side blind stops 32 and a head blind stop 34. Each blind stop 32 is provided with a dove-tailed tongue 36 adapted to interfit with a dove-tailed rabbet 38 formed in the side jamb 12. (See Figure 3.)

The side casing 16 projects slightly beyond the forward edge of the side jamb 12 at the base of the tongue 20 thereon so as to form, in conjunction with the rabbet 38, a dove-tailed groove to receive the dove-tailed tongue 36 of the side blind stop 32.

By this construction the blind stop 32 is held much more rigidly after the side casing is secured in position on the side jamb than when nails or screws only are used for securing the blind stop in position. Furthermore, it is much harder to remove the blind stop and burglars are not so ready to tamper with the window when provided with a dove-tailed blind stop as illustrated, inasmuch as the side casings would have to be removed before the blind stops and window sashes 40 could be removed.

The dove-tailed connections between the blind stops and side jambs are particularly desirable, but at the head of the window it is not so necessary for the blind stop 34 to have as much rigidity as the side blind stops 32. Consequently, the blind stop 34 may be rectangular in cross section and nailed in position, although it may be similarly rabbeted in position as illustrated in Figure 8. In this figure the dove-tailed tongue of the blind stop is indicated at 36a and the dove-tailed rabbet of the head jamb 14 is indicated by the reference numeral 38a. It will be noted that the head blind stop is rabbeted as indicated at 42 so as to make its outer face in alignment with the outer faces of the side blind stops 32.

It will be noted that the head jamb 14 in this figure is provided with a rabbet 44 to interfit with the rabbet 30a of the head casing 18. This is just another way of making a joint at the top of the window frame which will allow downward motion of the head jamb in assembly.

Some changes may be made in the construction and arrangement of the parts of my device, without departing from the real spirit and purpose of my invention, and it is my intention to cover by my claims, any modified forms of structure or use of mechanical equivalents, which may be reasonably included within their scope.

I claim as my invention:—

1. A window frame construction comprising side and head jamb members and side and head casings, joints between said jamb members and said casings for weather proofing purposes, said joints being arranged as follows for convenience in assembly; each of said side jamb members having a formed tongue and each of said side casings having a groove aligned and coacting therewith, said head casing being provided with a downwardly opening rabbet to coact with said head jamb member, the upper end of each of said side casings being provided with a tongue, the lower edge of said head casing being provided with a groove for coaction therewith, the alignment of said last mentioned groove and of said rabbet being such as to permit simultaneous assembly of said head casing with the tongue of the side casing and with the head jamb respectively by a single sliding motion downwardly in a plane parallel with the vertical plane of the side casing.
2. A window frame construction comprising side and head jamb members and side and head casings, joints between said side casings and said head casing and between said head jamb and said head casing for weather proofing purposes, said joints being arranged as follows for convenience in assembly; said head casing being provided with a downwardly opening rabbet to coact with said head jamb, the upper end of each of said side casings being provided with a tongue, the lower edge of said head casing being provided with a groove for coaction therewith, the alignment of said groove and of said rabbet being such as to permit simultaneous assembly of the head casing with the tongue of the side casing and with the head jamb respectively by a single motion downwardly in a plane parallel with the vertical plane of the side casings.

SERN MADSEN.
